(57) **CLAIM**

The ornamental design for a stand for television, as shown and described.

DESCRIPTION

FIG. 1 is a front perspective view of a stand for television, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a bottom perspective view thereof;

FIG. 10 is an enlarged view of the portion 10 in FIG. 8;

FIG. 11 is an enlarged view of the portion 11 in FIG. 9;

FIG. 12 is another front view thereof in a television environment;

FIG. 13 is another front perspective view thereof in a television environment;

FIG. 14 is another rear perspective view thereof in a television environment; and,

FIG. 15 is another front view thereof in an alternate position where the legs of the stand are adjusted to a wider angle in a television environment.

The even-dash broken lines depicting portions of the stand for television form no part of the claimed design. The dot-dot-dash broken lines surrounding portions of the claimed design that are illustrated in enlargements form no part of the claimed design. The even-dash broken lines depicting a television in FIGS. 12-15 are for illustrative purposes only and form no part of the claimed design.
